DISPENSING GUIDE FOR A BOXED COIL OF WIRE

Guido Zecchin, Winsted, Conn., assignor to
Hudson Wire Company, Ossining, N.Y.

Filed Sept. 10, 1969, Ser. No. 19,086

Term of patent 14 years

Int. Cl. D9—99

U.S. Cl. D52—1

FIG. 1

FIG. 6

FIG. 7

FIG. 1 is a perspective view of a dispensing guide for a boxed coil of wire;

FIG. 2 is a top plan view thereof;

FIG. 3 is a front elevational view thereof;

FIG. 4 is a bottom elevational view thereof;

FIG. 5 is a rear elevational view thereof;

FIG. 6 is a left-side elevational view thereof; and

FIG. 7 is a right-side elevational view thereof.

I claim:

The ornamental design for a dispensing guide for a boxed coil of wire, as shown.
